CLAIM

The ornamental design for LED packages, as shown and described herein.

DESCRIPTION

FIG. 1 is a bottom perspective view of an LED package according to the present invention.

FIG. 2 is a top view of the LED package shown in FIG. 1.

FIG. 3 is a bottom view of the LED package shown in FIG. 1.

FIG. 4 is a front elevation view of the LED package shown in FIG. 1.

FIG. 5 is a right side elevation view of the LED package shown in FIG. 1.

FIG. 6 is a back elevation view of the LED package shown in FIG. 1; and,

FIG. 7 is a left side elevation view of the LED package shown in FIG. 1.

The broken lines in the drawings are included to show portions of the article that form no part of the claimed design.

1 Claim, 2 Drawing Sheets
